AUTOMATIC IGNITER

Adam P. Kunowich, Decatur, Ind.

Application May 25, 1937, Serial No. 144,721

3 Claims. (Cl. 219—32)

This invention appertains to new and useful improvements in fire starters for ranges and more particularly to an automatic igniter whereby fires can be started in ranges and in other forms of stoves.

The principal object of the present invention is to provide an igniter of the character stated which can be set to take effect at some future time, and which in operation is substantially fool-proof and not susceptible to the ready development of defects.

Another important object of the invention is to provide an automatic igniter of the character stated, which is positive acting, and substantially simple in construction.

These and various other important objects and advantages of the invention will become apparent to the reader of the following specification.

20 In the drawings:

Figure 1 represents a front elevational view of a range with a portion broken away showing the igniter installed.

Figure 2 is a side elevational view of a range 25 with a portion broken away showing the igniter installed therein.

Figure 3 is a fragmentary side elevational view of the range constructed for the igniter.

Figure 4 is a horizontal sectional view through 30 the rear portion of the range showing in top plan the igniter assembly.

Figure 5 is a fragmentary bottom plan view of the igniter.

Figure 6 is a section on the line 6—6 of Figure 35 4.

Figure 7 is an enlarged longitudinal sectional view through the carrier for the igniting element.

Figure 8 is a fragmentary enlarged sectional 40 view on the line 8—8 of Figure 4.

Figure 9 is a fragmentary sectional view on the line 9—9 of Figure 4.

Figure 10 is a fragmentary vertical sectional view of the range.

45 Figure 11 is a front elevational view of the controller.

Figure 12 is a rear elevational view of the controller.

Figure 13 is a horizontal sectional view 50 through the controller.

Figure 14 is a perspective view of the contactor of the controller.

Referring to the drawings, wherein like numerals designate like parts, it can be seen in 55 the drawings that numeral 5 generally refers to

the range in the firebox 6' of which is located the igniter generally referred to by numeral 1. Numeral 8 represents the usual grate structure. This end of the range is provided with the door 9 which permits access to the igniter 1.

The igniter consists of an elongated plate of heat insulating material generally referred to by numeral 10 which is provided with a lateral flange 11 at its upper end and an inclining flange 12 at its lower portion. The plate 10 with its flanges 11 and 12 is provided with a metallic jacket 13.

In the bottom side of the flange 12 is secured as by bolts 14 the plate 15 of insulation to which the elongated U-shaped igniting element 16 is secured by a clamp or the like 17.

A block of insulation 18 is provided on one end of the plate 10 to which connections 19 are made from the cord 20 and which jumper 20 extends to the igniting element 16. This igniting element may be of any conventional design.

It will be observed in Figure 1, that this igniter has the declining flange portion 12 underlying a portion of the grate 8, and of course when inflammable material is placed on the grate 8 and the element 16 ignited, the inflammable material will quickly become ignited.

Numeral 21 generally refers to the controller which consists of the shell 22 having the clock-dial 23 at its front side. Numeral 24 represents the clock mechanism case. Observing Figure 13, it can be seen that numeral 25 denotes the winding key for the alarm mechanism of the clock 24, while numeral 26 denotes the hour hand setting shaft which in the present case has the collar 27 secured thereon to turn with the shaft and from this projects a plurality of fingers 28. The switch mechanism generally referred to by numeral 29 is located on the di-electric block 30 and includes the contactor arm 30' pivotally connected as at 31 to the post 32 and operative against the stationary contact 33. A pin 34 extends through the free end of the contactor 30 and on one end portion is the roller 35 which is prevented from displacement by the collar 36. The other end portion is denoted by numeral 37 and projects beyond the opposite side of the blade 30 and is in the path of one of the fingers 28 when the said blade 30 is engaged with contact 33.

It can be seen that numeral 38 denotes the time winder, while numeral 39 denotes the usual alarm off and on control.

In the upper portion of the cage 22 is the red lamp 40 which becomes illuminated when the

switch 29 is in closed position, and this light may be seen through opening 41 in front of the cage 22.

It can be seen in Figure 12 that a spiralled spring 42 has its inner end secured to the winding key 25 while its outer end is suitably secured, as by welding as at 43, to the outer convolution of the spring. This forms an eccentric.

It can now be seen, that when the clock mechanism has been set and the alarm goes off, the spring 42 will be carried downwardly so that its outermost convolution will strike the roller 35 and cause the blade 30 to be driven downwardly to engage the contact 33 thus closing an electrical circuit including the igniter 16. At the same time, the pin 37 is brought down to a position to be in the path of one of the fingers 28 projecting from the collar 27 on the hour hand setting shaft 26. As this shaft 26 rotates it will strike the pin end 37 and open the switch 30 after the switch has been closed for a suitable length of time. Thus the igniter is energized for starting the fire in the firebox 6 and then automatically deenergized.

While the foregoing specification sets forth the invention in specific terms, it is to be understood that numerous changes in the shape, size, and materials may be resorted to without departing from the spirit and scope of the invention as claimed hereinafter.

Having thus described the invention, what is claimed as new is:

1. An igniter of the character described comprising a vertically disposed plate of heat refractory material, a bracket, an adjustable connection between the upper edge of the plate and the bracket, a flange at the lower edge of the plate, and an igniting element secured to the bottom of said lower flange, said adjustable connection comprising a plurality of fastening elements, said flange at the upper edge of the plate formed with transverse slots through which and the bracket the securing elements are disposed. 10

2. An igniter of the character described comprising a vertically disposed plate of heat refractory material, a bracket, a connection between the upper edge of the plate and the bracket, a flange at the lower edge of the plate, and an igniting element secured to the bottom of said lower flange, said plate and its flanges being provided with a metallic encasement and a strip 15 of insulation between the encasement at the lower flange and the said igniting element. 20

3. An igniter of the class described comprising a vertically disposed plate of heat refractory material, a flange at the lower edge of the plate, a metallic casing enclosing the plate, a strip of insulation on one face of the flange, a U-shaped igniting element fastened to the strip and conductors connected with the ends of the legs of the U-shaped element. 25

ADAM P. KUNOWICH.
